(57) **CLAIM**

The ornamental design for a glove, as shown and described.

DESCRIPTION

FIG. 1 is a front, left and top perspective view of a glove design showing my new design.
FIG. 2 is a front view of a glove.
FIG. 3 is a rear view of a glove.
FIG. 4 is a left side view of a glove.
FIG. 5 is a right side view of a glove.
FIG. 6 is a top view of a glove; and,
FIG. 7 is a rear, right and bottom perspective view of a glove.

Any shading and cross-hatching are not features of the design but are utilized to illustrate the surface contours of the glove design in the drawings.

In the drawings, the broken lines illustrate portions of the article which form no part of the claimed design.
